DESIGN FOR A VEHICLE TRAILER

John W. Lavender, Opa Locka, Fla.

Application February 21, 1934, Serial No. 50,821

Term of patent 7 years

To all whom it may concern:

Be it known that I, JOHN W. LAVENDER, a citizen of the United States, residing at Opa Locka, in the county of Dade, and State of Florida, have invented a new, original, and ornamental Design for Vehicle Trailers, of which the following is a specification, reference being had to the accompanying drawing, forming part thereof.

In the drawing:

I claim:

The ornamental design for a vehicle trailer, as shown.

JOHN W. LAVENDER.
